Application March 10, 1938, Serial No. 195,068

2 Claims. (Cl. 281—25)

My invention relates to a new type of bound book in which the sheets or leaves are perforated along one edge and held together by a plurality of loops extending through said perforations.

5 The chief object of my invention is the production of a bound book, the sheets of which will lie substantially flat when the book is opened at any point.

10 Other objects will appear from the following description, reference being made to the accompanying drawing in which:

Figure 1 is a cross section of an assembly of sheets perforated preparatory to binding them together.

15 Figure 2 is a similar cross section with a piece of wire inserted through a line of the perforations.

20 Figure 3 is a similar view with the section of wire partly formed into a loop and a strip of binder's cloth placed over the ends of the wire.

Figure 4 shows the construction after the wire has been bent down over the binder's cloth.

25 Figure 5 shows the same structure with a strip of binder's board pressed against the wire and glued to the strip of binder's cloth.

Figure 6 is a plan view of a portion of the bound sheets.

Figure 7 is an end view, partly in section, of the bound book.

30 Figure 8 is a similar view of the bound book when open.

Figure 9 is a plan view of a perforated strip adapted to be used in replacing pages which have been torn out.

35 Figure 10 is a plan view of the same perforated strip pasted to a sheet.

Briefly stated, the method provided by this invention consists in perforating the sheets to be bound along one margin thereof, the perforations in all the sheets being the same and being

40 equally spaced, feeding strands of wire through the registered perforations, forming the lengths of wire into loops, placing a strip of binder's cloth over the ends of said wires, bending the wires down over said binder's cloth, and glueing a strip of binder's board to the binder's cloth.

45 Although it is usually preferable to make the loops of wire and to fasten them between a strip of binder's cloth and a strip of binder's board, it is evident that any material capable of being

50 formed in a loop and retaining its loop shape may be substituted for the wire and that such loops may be glued, cemented or otherwise fastened to binding strips of other materials.

55 Referring to Figures 1-5, sheets 1 are perfo-

rated as shown at 2 and stacked to register the perforations, wire 3 is inserted through each set of perforations and is formed into a loop as shown in Figure 3. In making this loop, I have found that the character and uniformity of the 5 loops is improved if the sheets of paper are compressed so that the interior walls of the holes formed by the registered perforations are substantially rigid. A strip of binder's cloth 4 next

is forced over the ends of the wire loops 3 and 10 the ends of these wire loops then are bent down over the binder's cloth 4 as shown in Figure 4.

I prefer to bend the extreme free ends of the wires outwardly to form short prongs 5. Although these prongs are not necessary, they will 15 improve the rigidity of the loops when the book is completed. A strip of binder's board 6 is then

glued to the binder's cloth 4 and the prongs 5, together with a substantial part of the flat side of 20 the wire loops 3, are pressed down into the binder's board. When all the perforations 2 have been

provided with wire loops attached to the binder's board, as shown in Figure 6, the book may be 25 provided with a cover secured in the conventional manner to the assembly just described as shown in Figure 7, the marginal portions of binder's cloth 4 extending laterally at opposite sides of the wires being attached to the sides of the cover 7. A reasonably satisfactory cover can be 30 secured in place by merely glueing the back of the strip of binder's board 6 to the cover, in which case the strip of binder's cloth does not need to extend beyond the wire loops.

Figure 9 represents a strip of thin Celluloid 8 which has been perforated as shown at 9, the 35 perforations corresponding to the wire loops 3.

Lines 10 represent cuts in the Celluloid which will permit the insertion of the wire loops as shown in Figure 10. The use of this strip permits 40 the insertion of a sheet after the book is bound. It is merely attached to the edge of sheet 11 as

shown in Figure 10 and the wire loops then are forced into the perforations 9 through the cuts 45 10. This strip may be made of any material of sufficient stiffness and tensile strength to hold 50 the sheet in the book after the strip has been cut along lines 10.

Having thus described my invention, what I 55 claim is:

1. A book comprising a plurality of sheets perforated, a plurality of loops of a material capable of holding its loop shape extending through the perforations of said sheets and of such size and so shaped that the sheets will readily turn upon them, one side of each of said loops ex- 55

tending over a strip of binder's cloth, and a strip of binder's board to which said cloth strip is adhesively fastened, said loops being pressed into the binder's board and held in place by the binder's cloth.

5 2. A book comprising a plurality of sheets perforated, a plurality of wire loops extending through the perforations of said sheets, the diameter of the wire being less than the diameter

of said perforations and the loops being formed in an elongated semi-circle, each wire being bent over a strip of binder's cloth, and a strip of binder's board to which said cloth strip is adhesively fastened, the ends of said wire loops 5 being pressed into the binder's board and held in place by the binder's cloth.

ROBERT C. MCKAY.
